VACUUM MOP CLEANING RECEPTACLE

Mary Kersky, Milwaukee, Wis.

Substituted for abandoned application Serial No. 77,657, May 4, 1936. This application September 17, 1945, Serial No. 616,867

3 Claims. (Cl. 15—310)

1

This invention relates to cleaning devices, and more particularly to a vacuum cleaner to clean such articles as dust mops and dust cloths.

Dust mop cleaners heretofore invented have been impractical, due, primarily, to insufficient suction, and secondly to their unwieldiness. A further disadvantage has been their lack of adaptability, as, for example, when such cleaners were designed to clean dust mops they could not clean dust or polishing cloths satisfactorily. This invention is a substitute for the device claimed and specified in my forfeited and now abandoned application, Serial Number 77,657, filed May 4, 1936.

One object of the present invention is to produce a vacuum cleaner for dust mops which will develop sufficient suction to clean them effectively.

Another object is to produce a vacuum cleaner which adapts itself readily to various sizes and types of cleaners, such as dust mops, dust cloths, etc.

A further object is to produce a vacuum cleaner for cleaning dust mops, dust cloths, etc., which occupies a minimum floor space.

Other objects are to produce a vacuum cleaner for dust mops and the like which may be easily stored and cleaned, and which is economical to manufacture and use.

The accompanying drawings illustrate one form of the invention. In the drawings:

Figure 1 is a vertical cross-section through the center of the cleaner.

Figure 2 is a cross-section on the line 2—2 of Figure 1, looking in the direction of the arrows; and

Figure 3 is a plan view of the top of the cleaner.

In the drawings, in which like numerals indicate like parts throughout the several views, a motor 10 is mounted in the bottom of a container 11, with the shaft 14 of the motor vertical.

A fan casing 12 is carried on the upper end of the motor and houses a fan 13 which is connected to and driven by the motor shaft 14. The fan 13 draws air in through an intake opening 15 in the upper side of the fan casing and expels it through an exhaust port 16 and into a dust bag 17 in a manner common to vacuum cleaners with centrifugal blowers.

A cone 20 is connected to the intake opening 15 at the apex, and diverges upwardly to meet the sides of the container. A second cone 21 mounted above the cone 20 and of lesser slope di-

verges upwardly from the center and is joined to the cone 20 and to the inner surface of the container at the outer edge of the cones to form a cleaning chamber 22 in the container above the cones and a suction chamber 23 between the cones.

A plurality of ports 24 through the surface of the upper cone 21 form a series of apertures through which the air is drawn at high velocity from the cleaning chamber 22 into the suction chamber 23. The air passes through the suction chamber 23 and into the fan 13 which discharges the dust laden air into the dust bag 17.

The dust bag is made to lie horizontal in the container 11 and partially surround the motor 10, as shown in Figure 2, thus giving a compact unit. The lower part of the container is provided with a screen door 25 through which the bag may be removed for cleaning. The screen allows air which has been drawn into the dust bag 17 and which has been expelled through the fabric of the dust bag to escape from the bottom of the container.

A cover 26 is provided for the container. The cover 26 is preferably made of fabric which will permit air to enter freely but which will prevent dust from being forced out of the cleaning chamber 22 by eddies.

The cover may be divided into four sections for convenience, and the sections connected by sliding fasteners 27, commonly known as zippers and shown enlarged in the circle inscribed in Figure 3. A dust mop may thus be inserted into the cleaning chamber 22 by opening three or four of the zippers 27, and the zippers closed tightly about the handle of the dust mop before shaking it. By opening only one zipper or two aligned zippers dust cloths may be inserted and shaken.

To clean a dust mop, three or four of the zippers 27 are unfastened and the mop inserted in the cleaning chamber 22. The zippers 27 are then fastened about the handle of the mop and the mop shaken and moved about in the chamber. As the mop moves over the various apertures 24 they are subjected to the relatively strong suction due to the restricted area of the apertures and the dirt is effectively removed.

Having thus described the invention, it is realized that it is susceptible to various changes and modifications, and it is not therefore desired to limit it to the precise form herein shown and described, but only by the scope of the appended claims.

What is claimed as new and desired to secure by Letters Patent is:

1. In a device of the character described comprising a casing, a cleaning chamber in the upper portion of said casing, a conical bottom to said chamber sloping inwardly and downwardly, and having a plurality of apertures therethrough, a second inwardly and more sharply downwardly sloping cone mounted below and fixed to the first cone at the peripheries of said cones to form a suction chamber therebetween, a suction fan connected to said suction chamber and a dust bag, said fan causing the air from said chamber to be forced into said dust bag.

2. In a device of the character described, a casing, a cleaning chamber in the upper portion of said casing, an inwardly and downwardly sloping cone attached to said casing and forming the bottom of the cleaning chamber, said cone having a plurality of perforations therethrough at different elevations thereon, an auxiliary cone below said cleaning chamber, said auxiliary cone provided with an opening at its extreme lower end, a motor in the lower part of said casing below said auxiliary cone, a fan driven by said motor and adapted to draw air and dust through said opening at the extreme lower end of said auxiliary cone and exhaust the same, and a dust bag within said casing, said dust bag in communication with the exhaust of said fan to receive air and dust discharged therefrom.

3. In a device of the character described, a casing, a cleaning chamber in the upper portion of said casing, an inwardly and downwardly sloping cone attached to said casing and forming the bottom of said cleaning chamber, said cone having a plurality of perforations therethrough at

different elevations thereon, a second cone fixed to said casing and below said first cone and converging downwardly to form a suction chamber between said cones, a fan in communication with said suction chamber to draw air and dust from said cleaning chamber through the perforations and the suction chamber, a dust bag receiving air and dust discharged from said fan, and an electric motor to drive said fan, said dust bag, fan and motor disposed within said casing.
